UNITED STATES PATENT OFFICE.

AXEL JULIUS LARSSON, OF RONNINGE, AND KALEB EMIL ERIKSSON, OF SALTS-JOBADEN, SWEDEN.

THERMOSTAT.

Application filed December 10, 1923. Serial No. 679,763.

To all whom it may concern:

Be it known that we, AXEL JULIUS LARSSON and KALEB EMIL ERIKSSON, subjects of the King of Sweden, residing at Ronninge, Sweden, and Saltsjobaden, Sweden, respectively, have invented certain new and useful Improvements in Thermostats, of which the following is a specification.

The present invention has for its object an improvement in thermostats for regulating the supply of steam or hot water or for the draining of water of condensation or the like, and in which the thermostat body consists of materials with different coefficients of heat expansion. According to the invention, the thermostat body consists of one or more units, each comprising a cross and a pair of straight strips, arranged on opposite sides of the cross and connecting opposite arm ends of the cross. The cross is made of a material which has a different coefficient of heat expansion than the material forming the strips, the cross also being manufactured in such a manner that one pair of opposite arm ends of the cross lie in a different plane than the other pair of opposite arm ends.

When two or more units are used, they are connected with each other in such a manner that one strip is common to two adjacent units.

In the accompanying drawings a constructional form of the invention is illustrated.

Fig. 1 is a side view of a thermostat consisting of eight units.

Fig. 2 is a top plan view of the same.

Fig. 3 is a side view of one of the straight strips, and

Fig. 4 is a plan view of the same.

Fig. 5 is a side view of the cross, and

Fig. 6 is a plan view of the same.

Referring to the drawings, the thermostat body consists of the members 1 and 2 of metals with two different coefficients of heat expansion, for instance invar and aluminum bronze. The members 1 may be of invar and are made as straight strips, while the members 2 are of cruciform shape. The different members are connected to each

other in such a manner that the ends of two opposite arms of a cross, are firmly connected by rivets 3 or the like to the ends of a strip 1 arranged at one side of the cross, while the two remaining ends of the same cross, in a similar way are connected to the ends of a second strip 1, situated at the opposite side of the cross. Two opposite ends of the next cross are then connected with the ends of one of the above mentioned strips, which thus is connected to two opposite ends on two crosses. By this arrangement a thermostat is obtained, which at a very small variation of temperature undergoes considerable expansion or contraction. When the temperature increases, the central parts of the crosses 2 are forced to move away from the intermediate parts of the strips 1, and thus the length of thermostat, formed of the combined units, is increased in a degree corresponding to the number of units. For facilitating the bending of the crosses 2 in a desired direction, each cross is arranged in such a manner that two opposite ends of the cross lie in a different plane than the other two ends.

Claims:

1. Thermostats for regulating the supply of steam, hot water or the draining of water of condensation or the like including a body consisting of materials with different coefficients of heat expansion, said body including a unit, consisting of a cross and a pair of single straight strips, said strips being arranged on opposite sides of the cross and connecting opposite arm ends of the cross, the cross being formed of a material having a different coefficient of heat expansion than the material of which the strips are manufactured, the cross also being arranged in such a manner that one pair of opposite arm ends lie in a different plane from the other pair of opposite arm ends.

2. A thermostat as claimed in claim 1 including a plurality of said units, one of the strips being common to and connected to opposite arm ends of two adjacent units.

AXEL JULIUS LARSSON.
KALEB EMIL ERIKSSON.
